UNITED STATES PATENT OFFICE.

JOHN HERZING, OF BRACKETTVILLE, TEXAS

CLOSURE LATCH.

Application filed July 24, 1925. Serial No. 45,360.

This invention relates to an improved latch for closures, having more particular reference to a closure which is especially, but not necessarily, designed for use in connection with swinging doors and the like.

Briefly, the invention resides in the provision of a pivotally mounted latch of right angular formation, wherein one arm is constructed for cooperation with a keeper and the other arm for connection with a spring pressed slidably mounted shaft carrying hand knobs for pulling and pushing the shaft for actuating the latch. A pivoted retainer is provided for cooperation with the latch to hold it against pivotal movement to prevent operation of the improved device whenever necessary.

The invention is characterized particularly by the pull and push actuation, the arrangement being such that when it is desired to open the closure from the outside, the outside knob is simply pulled, while to open it from the inside, the same is merely pushed.

Other features and advantages of the invention will become apparent from the following description and drawing.

In the accompanying drawing forming a part of this application and in which like numerals are employed to designate like parts throughout the same:

Figure 1 is a fragmentary sectional and elevational view showing a device constructed in accordance with the present invention with the latch in a locked state.

Fig. 2 is a detail section taken approximately upon the plane of the line 2-2 of Fig. 1.

Fig. 3 is a view similar to Fig. 2, but taken at a substantial right angle thereto.

In the drawing it is to be assumed that the device, as before stated, is applied to a horizontally swinging door which is indicated by the reference character 1. The frame is represented by the reference character 2, and it will be noted that this frame is provided with a recess 3 forming a keeper seat, adjacent which, is a base plate 4 having a portion extending over part of the recess to provide a shoulder. On the inner side of the door is a bracket 5 including a pair of spaced ears between which the central portion of a latch 6 is pivoted. The latch, as previously stated, is of right angular formation and one arm is provided with a nose 7 for cooperation with the aforesaid shoulder and keeper socket.

The other arm is detachably pivoted as at 8 to the enlarged portion of a sliding shaft 9. Said arm may be provided with an elongated slot to accommodate the pivot 8 thereby permitting sufficient lateral play around the pivot to eliminate any possibility of binding. This shaft is provided at its opposite ends with knobs 10 and 11 respectively. The door 1 is provided with a bored opening 60 in which a metal socket 12 is arranged. This socket is provided on its outer end with a spacing plate 13. A spring is confined within this socket and is connected with a shaft 9 in a manner to hold it in the approximate 65 position shown in Fig. 1, at which time the latch 6 will be caught.

In order to maintain the latch in the last named position, a pivoted retainer 15 is provided. This retainer comprises a strip 75 of metal having one end provided with a right angular finger piece 16 and the other end provided with a vertical right angular wedge 17 adapted to be located behind the adjacent arm of the latch to hold it in closed 80 position as shown in Fig. 1.

It is obvious that when the finger piece 16 is pressed downwardly, the retainer 15 is rocked about its pivot in a manner to move the wedge 17 to inoperative position. Now, 85 by pushing outwardly on the inside knob 10, the latch 6 will be rocked upon its pivot to release the door. Furthermore by pulling outwardly on the outer knob 11 when on the outside of the door, the same action will take 90 place. The coiled spring, however, will return the parts to normal locking position.

A careful consideration of the description in connection with the drawings will undoubtedly suffice to enable persons skilled in 95 the art to which the invention relates to obtain a clear understanding of the same. Therefore a more lengthy description is thought unnecessary.

While the preferred embodiment of the 100 invention has been shown and described, it is to be understood that minor changes coming within the field of invention claimed may be resorted to if desired.

Having thus described my invention, what 105 I claim as new is:

A door latch comprising a keeper secured on the frame for the door, a bracket secured on the door adjacent said keeper, a substantially right angular shaped latch pivotally 110 supported at its bend on the bracket, one end of one of the arms of the latch having a nose

formed thereon for cooperation with said keeper, a shaft extending transversely through the door and adapted for slidable movement actuating handles on the respective ends of the shaft, the free end of the other arm of the right angular shaped latch being pivotally secured to the shaft adjacent the inner end thereof, a coil spring associated with the shaft and with said closure 10 for holding the shaft in a predetermined position, the last mentioned arm of the right angular shaped latch having a notch formed

in the edge thereof, a lever pivotally supported intermediate its ends on the inner side of the door, a wedge shaped member formed 15 on one end of said lever and adapted for cooperation with said notch for holding the latch in a locked position, and a handle associated with the other end of the lever for actuating the same to permit the disengagement of the wedge shaped portion from the notch.

In testimony whereof I affix my signature.
JOHN HERZING.
